UNITED STATES PATENT OFFICE.

WILLIAM BARTON SPENCER, OF CHICAGO, ILLINOIS.

SHAFT-BEARING.

SPECIFICATION forming part of Letters Patent No. 703,492, dated July 1, 1902.

Application filed October 12, 1899. Serial No. 733,888. (No model.)

To all whom it may concern:

Be it known that I, WILLIAM BARTON SPENCER, a citizen of the United States, residing at Chicago, in the county of Cook and State 5 of Illinois, have invented a new and useful Shaft-Bearing, of which the following is a specification.

This invention relates to crank-shafts, and more particularly to the bearings therefor; 10 and it has for its object to provide a construction which may be adapted to the common form of crank-hanger to permit an arrangement of the bearings thereof, wherein the points of bearing at the ends of the shaft will 15 most nearly approach the planes of rotation of the cranks, the result being a lesser friction, a lesser tendency to longitudinal movement of the shaft, and a consequent greater efficiency.

20 A further object of the invention is to so construct the parts that they may be readily adjusted and also that foreign matter may be excluded from the bearing-surfaces.

Further objects and advantages will be apparent from the following description.

In the drawings forming a portion of this specification, and in which like numerals of reference indicate similar parts in the several views, Figure 1 is a side elevation showing 25 the complete construction applied to the crank-hanger. Fig. 2 is a vertical central section of Fig. 1, taken longitudinally and showing the crank-axle and portions of the cranks in elevation. Fig. 3 is a view similar to Fig. 30 2 and showing a modification. Fig. 4 is an elevation showing the interior of the crank-hub at one end of the shaft. Fig. 5 is a reverse view of Fig. 4.

Referring now to the drawings, 6 is the 40 crank-hanger, of usual shape, with the exception that the diameter thereof is increased at its ends to form cylindrical enlargements 7 and 8, which are externally threaded. The ends of this hanger are similarly equipped, 45 and each has mounted thereon and in engagement with its threads an internally-threaded sleeve 9, which projects outwardly and beyond the ends of the hanger. An inwardly-directed flange 10 is formed within each of 50 the sleeves 9 and at a slight distance from the outer end thereof, and the outer face of each of these flanges forms a race, a second

and coöperating race being formed upon the inner surface of each sleeve intermediate the flange 10 and the outer end of the sleeve. In 55 order to hold the sleeves 9 in proper adjustment upon the ends of the hanger 6, jam-nuts 11 are disposed upon the threads of the hanger and are adapted to exert pressure against the sleeves through the intermediate 60 washers 12.

Disposed in the hanger 6 is a crank-shaft 13, which is shown as having both ends threaded. Engaging the threads of the crank-shaft are the hubs 14 and 15 of the cranks 16 and 17, these hubs having each a groove 18 therein, which is angular in cross-section and one side of which groove forms a race which co-operates with the races carried by the adjacent sleeve 9 to receive bearing-balls 20, 70 which are disposed in engagement with these races.

As shown in the drawings, the flanges 22 and 23, which are the result of the formation of the grooves 18, project over and encircle 75 the outer ends of the sleeves 9 and are fitted thereto snugly, the flange 22 at its inner end carrying a sprocket 24. This flange 22 is of a length sufficient to project inwardly and beyond the adjacent balls 20, and thus supports the sprocket in a plane lying between the bearings at the opposite ends of the shaft. With this construction it will be seen that the balls within the flange 23 project into the plane of rotation of the crank 16, and thus is 85 the friction most easily distributed and the usual defects incident to the common arrangement of bearings eliminated. It will also be seen that when it is desired to adjust the bearings to compensate for wear the jam-nuts 11, which are provided with openings 90 25, may be engaged by a spanner to loosen them, after which the sleeves 9 may be similarly engaged through the medium of the openings 26, and the bearing-races carried by the sleeves 95 9, may be moved toward or away from the races carried by the hubs 14 and 15, and the crank-sprocket may be properly aligned with the rear sprocket.

In order to prevent disengagement of the 100 cranks from the crank-shaft when back-pedaling, the hubs 14 and 15 are held against rotation with respect to the shaft by means of screws 28, engaging the threads of perfora-

tions 29 in the hubs of the cranks, and which perforations extend into the adjacent portions of the crank-axle, these screws being, in effect, keys. Instead of having both crank-hubs thus engaged, however, one of the cranks may be made integral with the crank-shaft.

In Fig. 3 of the drawings is shown a modification in which no sleeve 9 is employed at the sprocket end of the crank-hanger, and instead, a bearing-cone is pressed or threaded into the end of the shell. By this means, the alinement of the sprocket, with the rear-wheel sprocket is not affected and the adjustment of both the bearings may be accomplished by manipulation of the sleeve at the opposite end of the hanger.

While the invention has been described in connection with a bicycle, it will of course be understood that it may be employed under any other conditions to which it is adapted and that in the manufacture of the construction various modifications may be made and any desired proportions and material used without departing from the spirit of the invention.

Having thus described the invention, what is claimed as new is—

The combination of a crank-hanger having enlarged end portions 7 and 8 provided with exterior screw-threads, the interiorly-threaded sleeves 9 arranged on the exterior of the end

portions of the crank-hanger and extending outward beyond the same and provided with inwardly-extending annular flanges 10 located between the ends of the sleeves 9 at points beyond the ends of the hanger and having their inner edges arranged substantially in alinement with the body portion of the hanger and forming ball-races with the outer portions of the sleeves 9, a crank-shaft extending through the hanger, cranks provided with hubs secured to the crank-shaft and provided with ball-race grooves 18, the inner portions of the hubs extending into the sleeves 9 beyond the intermediate flanges 10 and the outer portions of the hubs extending over the said sleeves 9 and arranged on the exterior of the same, balls located within the ball-races of the sleeves 9 and in the grooves 18 of the hubs, the jam-nuts 11 arranged on the threaded end portions of the hanger adjacent to the inner ends of the sleeves 9, and washers interposed between the jam-nuts and the sleeves, substantially as described.

In testimony that I claim the foregoing as my own I have hereto affixed my signature in the presence of two witnesses.

WILLIAM BARTON SPENCER.
